UNITED STATES PATENT OFFICE.

ALBERT G. SCHERER, OF CHICAGO, ILLINOIS, ASSIGNOR TO EXCELSIOR STEEL FURNACE COMPANY, OF CHICAGO, ILLINOIS, A CORPORATION OF ILLINOIS.

HEATING DEVICE.

Original application filed April 19, 1920, Serial No. 374,892. Divided and this application filed April 10, 1922. Serial No. 550,974.

To all whom it may concern:

Be it known that I, ALBERT G. SCHERER, a citizen of the United States, residing at Chicago, in the county of Cook and State of Illinois, have invented a new and useful Improvement in Heating Devices, of which the following is a specification.

My present invention relates to heating systems, and more particularly to the type known as the "monopipe" hot air system, that is, a furnace or heater from which a single large hot-air discharge pipe leads upwardly to a single register structure for the distribution of the hot-air and which generally receives the cool air returned to the furnace or heater for reheating through another portion of the same register structure.

When a register structure is to be placed in a position such as against a wall or upon both sides of a partition wall, as disclosed in my prior Letters Patents of February 3, 1920, Numbers 1,329,802 and 1,329,804, the vertical plane of the back of the register is, of course, parallel with the plane of the wall, and as this cannot be changed or moved difficulty may be encountered in making the installation owing to the fact that the front of the furnace or heater had to be parallel with the plane of the wall so that slight deviations therefrom meant considerable unnecessary labor and time in erecting the furnace or heater unless great care was used. Also it may be, and often is desirable to face the furnace with the coal and ash doors in front of bins or receptacles so as to more conveniently handle the coal and ashes, which of course could not be done where there is no adjustability or relative movement provided for between the register and the furnace structure.

In my present structure I have so co-related the furnace, the air supply and discharge pipes, and the register structure that much time and labor are saved in the erection of the furnace and the installation of the pipes and register structure, and to accomplish this co-relation of the elements, I have disposed the register structure above the furnace structure with their axes co-inciding or in longitudinal alinement. I am enabled by this construction to assemble the furnace and pipes and then swivel or rotate the register until its vertical plane is paral-

lel with the vertical plane of the wall against which the register is placed. Also, I am enabled to dispense with considerable pipe between the floor and the top of the furnace or heater, and, to a great extent, make use of stock or commercial pipes, boots and boxes in the erection of the entire structure, thereby dispensing with specially formed elements that are expensive in manufacture and to replace. Other objects and advantages will be obvious to others skilled in the art after an understanding of my invention is had, and I prefer to accomplish these divers objects in substantially the manner herein-after described and as illustrated in the accompanying drawings that form a part of this specification, in which

Fig. 1 is a vertical front elevation of my invention, portions of the walls whereof are broken away and in section to more clearly disclose the structure.

Fig. 2 is a transverse horizontal section slightly above the floor line. Figure 3 is a vertical side elevation of the structure illustrated in Fig. 1.

Fig. 4 is a vertical section of a fragmental portion of the structure substantially below the floor line, drawn to an enlarged scale, and illustrating the details and co-operative arrangement of the elements or members for permitting the adjustment thereof.

Fig. 5 is a fragmentary view illustrating the usual assembly of the furnace and register structures.

In carrying out my invention any suitable register structures may be employed for the discharge of the warm air and return of the cool air, I prefer, however, to make use of register structures, similar to those disclosed in my prior Letters Patent of the United States, and my pending application Serial No. 374,892 for Letters Patent of the United States, filed April 19, 1920; which matured May 30, 1922, in Letters Patent No. 1,417,772, (of which the present application is a division), wherein reticulated walls extend above the level of the floor and partially or wholly surround a two-compartment chamber for hot and cold air, although it will be understood that ordinary floor registers or floor grilles may be used as well.

Briefly stated, the register body shown in my present application comprises two metal

plates 10 forming the double rear wall that extends forwardly at its vertical end portions to provide imperforate portions 11 of the side walls. Angular straps or rings bent 5 U-shape in outline, such as the floor ring 14 are secured to and extend forwardly from portions 11 of the side walls and the upper and lower reticulated walls or grilles 15 and 16 are fitted to the rings with the bottom 10 edge of the lower grille resting upon the floor ring 14 that surrounds the opening made in the floor. Lateral flanges 17 on the ends of the grilles are connected by bolts 18 to angle-pieces 19 on the side plates 11.

15 Two vertically disposed converging walls 24 extend forwardly towards each other from the opposite corners formed by side plates 11 and rear walls 10 and meet at a point slightly to the rear of the front portions of the lower grille. The upper edges of these walls terminate at approximately one-half the height of the register, while their lower portions extend a suitable distance below the strap or ring 14, the purpose whereof will shortly be explained. It might be here stated, however, that said walls 24, together with rear wall 10, provide the triangular shaped upper portion of the hot-air passageway, and are a continuation of the hot-air conduit leading from the furnace structure below the floor, and said walls 24 also divide the interior of the lower portion of the register into two substantially equal portions, the outer 30 whereof is for cool air. Each wall 24 has a triangular shaped recess 25 (Fig. 1) extending downwardly from its upper edge in order to receive the edges of twin deflectors 26 of pyramidal shape and having their apices inverted, as seen in Fig. 1, so that they flare outwardly towards and meet the front and side walls or grilles of the register structure. From the foregoing it will be seen the register is open upon its front 45 and both sides, and there is no interference or retarding of the two currents of air because of the fact that the heated air is discharged through the upper grille in an upward and outward direction, while the cool air is moving towards the register in substantially a horizontal direction, and is taken in through the lower grille, as indicated by the arrows in Fig. 5.

The upper edge of the furnace shell or 55 casing 13 carries a T-section annulus or ring 28 from which a frustum conical shaped bonnet 29 extends inwardly at about a 45-degree angle, and a cylindrical pipe 30 is secured to the upper edge of the bonnet so 60 that its axis is in longitudinal alinement with the axis of the furnace casing. Telescoping with pipe 30 is a similar pipe 31, as seen in Figs. 1 and 3 to permit of adjustment for the varying distances between 65 bonnet 29 and the floor supporting the reg-

ister as well as to permit of the rotation of pipe 31 and its connected parts independently of pipe 30, as will presently be described. An adapter 32 connects pipe 31 with the lower portion of converging walls 24 and rear wall 10, and in order to do this the lower edge 32a of the adapter is made round or cylindrical to fit pipe 31; its rear portion 32b is fan-shaped or flared towards its top to meet the straight edge of wall 10 75 of the register; and the remaining upper portion is parallel with walls 24, or, in other words, the upper edge of the adapter 32 is triangular, while its lower edge is round, the sides merging into each other to provide 80 this peculiar shape. A pocket or seat 33 is formed at the upper edge of the adapter by bending the metal down and then up to receive and have the lower edges of one plate of walls 10 and wall 24 secured thereto, thus providing a hot or warm air passageway from the hot-air chamber within the shell to the hot-air passageway of the register.

Resting upon the flange or annulus 28 is 85 a cylindrical wall 34 the upper edge whereof terminates slightly above the horizontal plane of the top of bonnet 29 and is provided with a plurality of openings 35 to which cold-air return pipes 12 are connected and lead to and discharge the return air into the lower portion of shell 13. A T-section annulus or ring 36 is mounted upon the upper edge of wall 34, while an outer bonnet formed of a converging wall 37, of 90 somewhat frustum conical shape, has its lower cylindrical flange 38 resting upon the lateral member of annulus 36, as illustrated in detail in Fig. 4 of the drawings. Another T-shape annulus 39 is fitted to the upper edge of outer bonnet 37 and is secured thereto by bands 40, substantially in the manner shown in Fig. 4. I have, however, shaped annulus 39 to conform approximately to the contour of the lower edge of 100 the register structure,—that is it is substantially rectangular,—and the sides of the walls 37 of the bonnet merge into each other to conform therewith at their upper edge while retaining their circular or cylindrical shape at the lower edge.

In order to make connection between this outer bonnet or conical wall 37 and the lower portion of the register front, side and rear walls, I secure a sheet metal apron 41 to the inside face of the vertical flange of lower strap 14 so that said apron depends therefrom and passes through the opening in the floor. A skirting 42 is now cut from sheet metal of a width corresponding with the distance between strap 14 and annulus 39. This skirting is made preferably in two pieces the edges overlapping and has oppositely arranged angle brackets 43 that may be drawn towards each other by clamping 115

120

125

130

bolts 44 passed through the laterally projecting members thereof. This completes the passageway that conveys the cool air received by the register through the lower 5 grille 16 down between the adapter and skirting, then over the bonnet 29 between the latter and cylindrical wall 34, and discharges the same through apertures 35 to the return pipes 12 leading down into the 10 furnace shell 13.

In setting up or assembling the structure, the register is placed on the floor after the proper opening has been made therein, and in building up the furnace shell and 15 superposed structure, walls 34 and 37 may be rotated to aline annulus 39 with apron 41 without having to move the furnace, and the register may be rotated to aline it with the wall of the building against which it 20 is to be fitted at the same time rotating adapter 32 with its telescoping wall 31 on the fixed wall 30 of the hot-air passageway. This will permit of setting the furnace so that its feed and ash doors are in 25 any desired position, as, for example, conveniently in front of a bin or the like without regard to the vertical plane of the wall against which the back of the register is to be placed as the structure above the furnace shell may afterwards be rotated to 30 aline the register with the wall. When properly adjusted, skirting 42 is cut the proper height and secured in place, thus saving considerable time and labor in assembling the entire structure.

I am aware that divers changes or alterations may be made without departing from the principles herein described, but I desire it understood that all such modifications are 40 contemplated within the scope of the appended claims. In this connection, I wish to state the drawings and description herein given are merely typical and I do not

limit myself to the precise structure shown and described.

What I claim is:—

1. The combination with a register structure and a conduit leading into the same, of a furnace casing of cylindrical shape, a bonnet mounted upon the top thereof and 50 having a central opening, telescoping pipes connected respectively to said bonnet around said opening and to said conduit, a cylindrical wall extended above said casing, a second bonnet mounted upon said cylindrical wall and having rotative movement with respect thereto, and a wall substantially conforming to the contour of said register and second bonnet clamped to the adjacent edges thereof.

2. A device of the kind described comprising the exterior casing of a furnace, a structure above said casing having inner and outer conduits, a bonnet mounted on the top of said casing, means revolvably connecting said bonnet to said inner conduit, and other means revolvably connecting the top of the furnace casing with the outer conduit.

3. A device of the kind described comprising a furnace casing, a bonnet mounted thereon, a conduit wall connected to the upper portion of said bonnet and establishing communication with the interior of the casing, a short cylindrical wall mounted upon said casing and capable of rotatable adjustment thereon, a second bonnet mounted on said cylindrical wall, and a conduit wall connected to the upper portion of said second bonnet and spaced from said first 80 conduit wall, whereby said furnace casing may be rotated bodily with respect to the structure above the same.

Signed at Chicago, county of Cook, and State of Illinois, this 7th day of April, 1922.

ALBERT G. SCHERER.
